UNITED STATES PATENT OFFICE

MERRILL M. KISTNER, OF INDIANAPOLIS, INDIANA

WRINGER

Application filed, November 25, 1927. Serial No. 235,406.

This invention relates to automatic wringers.

One of the objects of the invention is in the provision of an automatic wringer, the safety mechanism thereof cooperating with the clutch mechanism for the wringer in a manner to disconnect the clutch when the safety device is operated.

Another object is in the provision of a fully automatic wringer, the same operating upon the manual release of the safety mechanism to insure unclutching of the wringer.

Still another object is in the provision of a clutch operating lever controlled by the movement of the safety release mechanism to unclutch the wringer drive shaft.

A further object lies in the combination of automatically operating clutch mechanism connected with the safety mechanism for the wringer for operating the wringer drive shaft, and a manually operable clutch member capable of controlling the movement of the wringer drive shaft.

A still further object lies in the provision of automatically operated safety release and clutch mechanism for wringers, the result obtained being to insure release of the safety mechanism by the operator when the washing operation has been finished, thereby releasing the tension between the wringer rolls and preventing same from being distorted by continued pressure in a non-rotatable position.

Other objects of the invention will appear in the following specification, taken in connection with the annexed drawings, in which—

Fig. 1 is a side elevation, partially in section, showing in detail my fully automatic release mechanism as applied to conventional wringer structure;

Fig. 2 is a plan view, parts being broken away to illustrate the safety mechanism;

Fig. 3 is a section on lines 3—3 of Fig. 2 looking in the direction of the arrows; and

Fig. 4 is a section along lines 4—4 of Fig. 1.

In a well known type of wringer mechanism, the lower roller is mounted in a stationary frame member and the cooperating upper roller is carried by a second frame

which is pivotally mounted so as to swing laterally with respect to the stationary frame. Pivotal movement of the upper frame and its associated roller is effective to release the tension normally existing between the rollers and therefore is a safety expedient resorted to in times of danger such, for example, as when the hand or clothes of the operator become entangled in the rollers. Release of all pressure between the rollers is also desirable when the wringer is in disuse to thereby prevent flattening and distortion of the roller surfaces.

As far as the applicant is aware, the only means for controlling the driving of the rollers in this type of wringer has consisted of the main clutch handle mounted on the head of the wringer. In other words, while release of pressure between the rollers could be effected by moving the upper roller frame, the rollers would continue to rotate until the main clutch handle was operated. Because of the distinctive and separate operations involved, it was seldom that the operator had the forethought to do both, especially upon cessation of the wringer operation. Usually the main clutch was thrown out to stop rotation of the rollers but the latter were left under tension, and flattening and distortion resulted.

The present invention proposes to provide mechanism for disengaging the clutch upon movement of the upper frame to pressure-releasing position. By this construction, the operator will learn to control the machine through the safety mechanism generally, and will move the upper frame into pressure-releasing position upon cessation of operation because, by so doing, the rotation of the rollers will also be stopped. Thus, the desirable result of releasing the pressure between the rollers following the wringing operation will be attained.

In the drawings, the present invention is illustrated in connection with conventional and known wringer structure, which includes a lower frame portion 10, an upper frame portion 11, carrying in bearings contained therein the upper wringer roll 12. A horizontally disposed spring 13 applies pres-

sure to the upper wringer roll and urges the latter into contact with the lower wringer roll 14, which in turn is held in suitable bearings in the lower frame 10. Means for applying 5 variable tension to the horizontal tension spring 13 is contained in the manually movable control handle 15. The manner of attaching the frame 11 to the frame 10 in the present instance includes spring clamp portions 16 and 17 secured to the upper frame, as at 18 and 19. The lower ends of the clamp portions 16 and 17 are not only spring tensioned, but bifurcated in a manner to overlap and engage two pairs of projecting lugs 20 and 21 disposed upon either end of the lower frame 10. The above mentioned clamps normally engage these lugs in a manner to hold the upper frame in a fixed position with respect to the lower frame. This spring tensioned lug connection also permits safety release mechanism to be disposed upon either side of the wringer and to permit pivoting of the wringer upon these lugs as well as release in either direction.

25 This safety release mechanism includes the horizontally disposed guard portions 22 and 23, which are pivoted at the dual points 24 and 25 on either side of the wringer. Laterally projecting pairs of lugs 26 and 27 upon the ends of the guard members 22 and 23 are capable of engaging the outwardly projecting cam portions 28 and 29 fashioned on the lower ends of the spring tensioned bifurcated clamps 16 and 17. The result is 35 that downward movement of the guard members 22 and 23 operates to move the cam portions 28 and 29 away from the projecting lugs 26 and 27 in a manner to release the head portion depending upon which side the horizontal member is located. The result is that the upper portion of the wringer frame is released and pivoted in a manner to release the pressure between the wringer rolls.

40 Applicant has described only one type of safety mechanism for wringers, and as a matter of fact, his present fully automatic control for wringers might well be applied to any type of safety release mechanism, either now known or later to be developed, which is 45 capable of releasing the pressure between the wringer rolls to prevent accident.

45 Turning now more particularly to applicant's new developments in control for wringers, the driveshaft for the lower wringer roll projects outwardly from the wringer at 50. A similar horizontally disposed drive shaft is shown at 31, contained and supported in bearings 32 in the wringer head. The wringer head, as shown herein is conventional and includes the outer casing 33, a rearward bearing support 34 for the horizontally disposed wringer shaft 31, a bevel gear 35 secured to the upper end of the vertical drive shaft 36, oppositely disposed bevel 55 gears 37 and 38, the rearward portions of

same designated 39 and 40 respectively, cooperating with the housing 33 in a manner to form not only bearing supports for themselves but also for the horizontal wringer shaft. A conventional clutch 41 is slidably and fixedly mounted upon the wringer shaft and is controlled by a clutch portion 42, which comprises the lower end of a manually controlled lever 43 extending exteriorly of the wringer head. This wringer head construction is entirely conventional, and the operating lever 43 is capable either of maintaining the wringer shaft in a neutral position or permitting a forward or reverse movement of the wringer rolls. As a matter of fact, the wringer and the wringer head construction heretofore described is conventional.

55 Applicant has now devised mechanism which combines the safety release mechanism of the wringer with the clutch controlling the movement of the wringer drive shafts 30 and 31. A female clutch portion 44 is securely attached, as at 45, to the projecting end of the wringer drive shaft 31. A male clutch portion 46 is slidably but fixedly connected to the projecting end of the horizontally disposed wringer drive shaft 30. A coil spring 47 normally tends to hold the male clutch portion 46 in engagement with the female clutch portion 44. A clutch controlling lever 48 is pivoted at 49 within a housing 50, which connects the wringer head with the wringer itself, there also being shown the physical connecting means 51 between the wringer and this housing. The clutch control lever 48 may be controlled manually by means of the manually operable control lever 52 having the cam portion 53 engaging the upper and projecting end of the clutch control lever 48 in a manner to move same laterally to disconnect the clutch and therefore stop the movement of the wringer rolls. Similarly, movement of the manual control lever 52 to the full line position shown in the drawings will result in the coil spring forcing the male clutch portion 46 again into connection with the female portion 44, therefore permitting movement of the wringer rolls. The control lever 48, however, has a sliding pivotal engagement, as at 54, with the horizontally disposed lever 55, which is in turn pivotally engaged, as at 56, by a substantially vertically disposed lever 57, the same having a cam fashioned upper portion, said lever 57 being pivoted, as at 58, in the housing portion 50. The upper end of the lever 57 is cam fashioned, as previously described, and is adapted to be engaged and moved by a cam 59 disposed upon one end of the upper frame 11 of the wringer. This cam 59 is fashioned, as clearly seen in the drawings, in a manner to permit engagement of the clutch faces previously described only when the upper wringer frame is in the vertical or rather normal position, that is, 65 normal as respects the operation of the wringer.

er rolls. This cam portion 59, however, is fashioned to permit the lever 57 to move inwardly upon being released by said cam portion 59, and thus unclutch the wringer drive shafts whenever the head is tilted to either side, this tilting, of course, being controlled by the safety release mechanism previously described. As respects the inner movement of the lever 57, when released by the cam 59, it might be stated that said inner movement is caused by the coil spring 58a, said spring being considerably stronger than the before mentioned spring 47 and adapted to overcome said spring when the lever 57 is released by the cam 59. This coil spring 57a abuts on one side the lever 57 and upon the other side a washer 57b fixedly attached to the wringer drive shaft. This washer also acts as an abutment means for the previously described coil spring 47. In other words, whenever the safety release mechanism is operated, the clutch controlling the wringer drive shaft is moved to an unclutched position, therefore stopping the wringer drive. Although applicant has shown a manual control lever 52 for this new type of automatically operating clutch mechanism for wringers, it is apparent that this control member might readily be dispensed with. However, inasmuch as the control of the movement of the wringer rolls is so intimately connected with the safety mechanism for the wringer, it is unlikely that this control mechanism would ordinarily be used at all, and that the operator would utilize the manual control lever 43 for changing the direction of movement of the wringer rolls, and would use at all times the wringer safety mechanism for unclutching the wringer drive shaft.

40 To explain more clearly this insuring that the operator will utilize this safety mechanism, it might be stated that previously even if the operator did release the safety mechanism, which possibly he did in many instances, nevertheless, this would not stop the movement of the wringer rolls and would require further manual manipulation of a lever to stop same. Now, when the operator finds that by merely releasing the safety mechanism he will not only relieve the pressure between the rolls and save the rolls, but will also stop the wringer drive shaft, it is practically certain that this mechanism will be used rather than the manual control lever 43. It would also be possible, of course, with the present mechanism, to have merely the control lever 43 capable of controlling the direction of movement of the rolls and of starting and stopping the same. However, applicant has shown a fully automatic control mechanism cooperating with the safety control mechanism to insure the stopping of the wringer rolls whenever the safety release mechanism is operated.

45 As respects the operation of the present

wringer mechanism, whenever the operator has finished the washing operation and desires to wring the clothes, he will move the wringer head to an upright position, which will immediately place the safety mechanism in readiness to be operated, as well as move the clutch mechanism to immediately start rotation of the wringer rolls. The movement of the frame to a vertical position will also create pressure between the wringer rolls, which may be adjusted, if required.

Now, when the wringing operation has been completed, the operator, realizing that it is highly desirable that pressure be relieved between the wringer rolls, and his attention being further called to this point, due to the fact that the wringer rolls are still moving, he immediately releases the safety mechanism, which automatically throws out the clutch to the lower wringer roll. In view of this fully automatic arrangement, it is not only highly probable but practically certain that the operator will utilize this single means for controlling the wringer operation, rather than resort to the dual manual operation of first stopping the wringer rolls and thereafter releasing the safety mechanism.

Obviously, if the operator can accomplish the same result in one movement, he will certainly resort to this one operation, and further, the fact that the safety mechanism is more readily within the grasp and more quickly operated will certainly lead him to resort to the quickest method of wringer control.

What I claim is:

In a wringer, the combination with a lower frame member, a wringer roller mounted therein, an upper frame member, a cooperating wringer roller mounted in the upper frame member, the said upper frame member being pivoted so as to move relatively to the lower frame and release the pressure between the rollers, releasable means for locking the frame member against movement when the rollers are in normal cooperating position, manually operated means for releasing the locking means, driving means for the rollers including a clutch member, and means controlled by the movement of the upper frame during its pivotal movement for disengaging the clutch.

In testimony whereof I have hereunto affixed my signature.
